FREDERICK MYERS, OF NEW YORK, N. Y.

Letters Patent No. 74,407, dated February 11, 1868.

IMPROVEMENT IN MACHINES FOR BUNDLING KINDLING-WOOD.

The Schedule referred to in these Letters Patent and making part of the same.

TO ALL WHOM IT MAY CONCERN:

Be it known that I, FREDERICK MYERS, of the city, county, and State of New York, have invented a new and improved Machine for Bundling and Tying Kindling-Fagots; and I do hereby declare that the following is a full, clear, and exact description thereof, which will enable those skilled in the art to make and use the same, reference being had to the accompanying drawings, forming part of this specification, in which—

Figure 1 is a transverse vertical section through middle of the machine.

Figure 2 is a cross-section of the same, through the line $x x'$, fig. 1.

Figure 3 is a plan view of the parts below the line $y y'$, fig. 2.

Figure 4 is a detail section of the clamps.

Figure 5 is a detail side elevation of the chute.

Figure 6 is a bundle of the fagots bound with the wire.

Figure 7 is a detail view of catch in the bottom of the boxes.

Figure 8 is a detail view of a portion of one of the clamps, exhibiting the points for confining the wire.

Similar letters of reference indicate corresponding parts.

This invention relates to an improved machine for bundling and tying fagots of kindling-wood in a form ready for sale. It consists of boxes passing under a chute, from which they receive the fagots, and conveying the same to a position over movable clamps. The bottoms, d , of the boxes, being provided with hinges, d , then open and discharge the wood into the clamps, which are then closed by the action of cams. A binding-wire then passes around the wood in a groove in the clamps, and is cut off and locked. The clamps then relax slightly, and the bundle of fagots thus made is delivered from the clamps by means of a plunger-disk acting against the side of the bundle, thereby thrusting the latter on to a slide, by which it is delivered from the machine.

The operations of the several parts producing this result will now be more fully explained.

$A'' A A A A$ are rollers, revolving on shafts $A' A' A' A' A'$, and carrying an endless belt, B , said rollers having bearings in the general frame, C , of the machine. Boxes D are attached to the said belt. A chute, E'' , in a fixed position above the frame, is provided with guides, e , forming a slot, e' , in which movable bottoms, e'' and e''' , slide. The boxes D pass under this chute, and the forward end of the passing box strikes against the bottom e'' , and pushes it along on its guides, thus removing the said bottom from under the chute E'' , and letting down a quantity of wood fagots into the box. As the filled box passes on, the bottom, e''' , is made to follow closely after, and in contact with the rear end of the box, so that the throat of the chute is not left an instant open. This following motion of the bottom, e'' , is accomplished by means of a slotted plate, j , pivoted to e''' at j' , fig. 5, and in the slot of said plate the pin r''' of the bottom, e'' , travels the entire length of the slot, thus allowing the bottom, e'' , to move the required distance before it draws the bottom, e''' , after it. A spring of rubber or metal—the former being the better material—is attached to the pins r'''' on the bottom, e'' , the other end of said spring being secured to some fixed point, as the plate P . One of these springs is shown in fig. 5, and lettered o . The function of this spring is to bring back, by its contractile tension, the bottom, e'' , to its normal position under the throat of the chute, when it has, by ascending the inclined portion of its slide, become disengaged from the forward end of the box D . The said bottoms travel in their slides by means of pins r'''' , two in number on each side of each bottom, whereby the latter can pass the angles in the slides. A continuous tongue working in the slide would not pass the said angles. When the bottom, e'' , passes from underneath the chute and enters the inclined part of the slide, it is borne upward from the box, and the edge of the bottom, e'' , is at length disengaged from the box by rising above the latter, and, obeying the tension of the spring o , flies back to its first position, which closes the lower throat of the chute. In doing so, it strikes forcibly against the bottom, e''' , (which was drawn by the said slotted plate j , so as to close the chute immediately after the filled box passed forward,) forcing it back, when both bottoms are then in position to repeat their functions. When another box passes. The guides e are attached to the chute, as shown in fig. 5, the plate P serving to secure the rear end of the under one. Standards E'' support the chute on the frame, as shown. These standards have slots, u' , fig. 5, which allow the chute, by means of a clamp-screw, u'' , to be adjusted up or down, thus regulating the contact of the box with the edge of the bottom, e'' . The chute is inclined, so that the fag-

ots may slide down regularly and fall parallel to each other into the boxes, and the inclination serves at the same time to prevent the fagots from pressing too heavily upon the bottoms, thus hindering their action. This chute is designed to take the fagots from a splitting-machine now in use, which has knives acting laterally against the savon-block, whereby the fagots fall into the chute and slide down it sidewise to the throat.

I will now describe the other parts, which act in connection with those above described.

G' G' are the clamps for holding the wood. They are semicircular, and are pivoted together at u by a pivot passing through the plate g^2 , as shown at fig. 2. The clamps have projections, g , working in slots, g^1 , in the bottom plate g , figs. 2 and 3, for the purpose of steadyng them. r r are friction-rollers, working on pivots r' r' , through lugs on the exterior of the clamps. H H' are toothed wheels, on their respective shafts F F'. Cams E E' are keyed on the said shafts F F'. The wheel H receives its motion from a pinion, K, keyed on a shaft, L, at the extremity of which is attached a crank-wheel, M, with its crank-handle M', both shown in dotted lines, though in practice the crank-wheel is substituted for a pulley, for the application of steam or other power. I is an idle-wheel, for transmitting the motion from H to H', whereby the cam E' and other parts are operated. This wheel I is on the end of a shaft, I', having bearings, I'', in the frame C, fig. 2. The teeth of H' engage with a toothed wheel, J, keyed on the same shaft, A', as the roller A'', whereby the belts B, working on A'', and the rollers A, are moved. These wheels and rollers have bearings in the general frame C, as shown, and which do not require minute description. Though the cams revolve in different directions, they are keyed on their shafts in such correlation with the clamps and each other, that they will present the same point of each to the rollers r , and actuate the clamps with the same degree of force at the same time. The clamps are provided with springs, s , following the general contour of the cam, and form the bearing-surface of the same. These springs are bolted to the cam at s''' , figs. 1 and 4, and pass around to the screw s'' , near the point of the cam. A slot, s' , in the spring s , which encloses the necks of the screws s'' , allows them a yielding motion on the said screws. The object of this spring is to furnish a yielding surface to the profile of the cam, so that if, from any cause, such as knots in the fagots, the clamps do not shut completely, the cams will pass by the rollers r without injury, closing the cams as much as may be, thus allowing the machine to continue its work without stoppage. A spring, e, on the meeting face of the clamp G, as shown in figs. 1 and 4, prevents any of the fagots from rising, when the clamps, from the causes aforesaid, do not close completely. The boxes, four in number, are arranged on the belt in the relative positions shown, and when so arranged will pass in harmony with the other parts of the machine when the whole is in operation.

Fig. 7 shows the action of an arm, b, fixed on the frame C, which disengages the spring-catch a'' for holding the bottom, d' , of the box shut. And the said arm is so situated that this disengagement will take place when the box is immediately over the clamps, which latter, from their own weight, stand open when not actuated by the cams, as before described. The box receives its fagots from the chute, and is borne on the belts B to the point over the clamps, and the arm, just described, liberates the catch a'' , when the bottom, d' , swings downward, and the fagots fall into the clamps. The box then passes on, and the cams E E', coming in contact with the rollers r r , close the clamps G G', which hold the wood firmly therein. A spool, N, figs. 1 and 3, contains the binding-wire n wound thereon. This spool revolves on a vertical spindle fixed in the plate N', standing out from the frame C, as shown. This wire is drawn off from the spool by the rollers h h , between which it passes, and is conducted on through the hollow shaft p of the bevel-pinions X and O, figs. 1 and 3. Emerging thence, it passes on between the edge of a cutter, f, and a notched plate, l, for receiving the points of the said cutter. Passing on, it enters a slot, m' , in a vertical spindle, m, figs. 1 and 3. After passing through this slot, the wire continues along over a lifter, n', working in the groove of the clamp G, and finally enters the groove, passing around in it, and also around the exterior of the body of fagots, which the said groove surrounds, as shown at fig. 4. The wire then emerges from the groove, and again passes through the slot m' , as shown in fig. 4 also. The cutter f then is thrust in and severs the wire, after which the bevel-wheel O', to which the spindle n is fixed, revolves and twists the ends of the wire, thus locking its ends securely, as shown at fig. 6.

The wheels connecting with and actuating the rollers which move the wire, the cutter, and twisting-spindle, will be hereinafter described.

The groove in the clamps is shown, with the wire lying therein in a detail section, at fig. 4, where also can be seen the lifter n' pivoted, as shown in the clamp G, and having a bent arm, n'' , (see corresponding part of fig. 1,) where this lever n''' is shown pivoted to a lug, g''' , attached to the frame C. A pin, b', standing out horizontally from the side of the cam E, strikes against the lever n''' , when the cam revolves, and, by the said connections, the lifter n' is thrown up, bearing with it the wire n , so that the two ends of the wires (for the lifter does not rise till the cutter has severed the wire) are brought together for twisting. The clamps are formed each of three pieces bolted together, as shown by the sections of rivets, 1, 2, 3, 4, figs. 1 and 4. The middle piece, being narrower than the outer ones, leaves the aforesaid groove, which surrounds the fagots when in the clamps, and permits the wire to pass freely around the former. Two small projecting points, standing out from the inner faces of the groove, prevent the wire from springing, so that its passing end will not catch against any of the fagots. The number of these may be increased, if found desirable. These points are located at b'' , fig. 1, and are shown attached to the clamp G b'' at fig. 8, that point being found, by experiment, the place where they are needed.

A nut and spring, N'', figs. 1 and 3, on the spool N, enables the latter to be adjusted with reference to its friction, whereby the wire is drawn off with greater or less facility, as circumstances may require. The spindle m enters the clamp G' in an opening, m'' , in the latter, figs. 1, 2, and 4. A half wheel, S, shown dotted in fig. 1, is keyed on the shaft F'. Its teeth engage with a pinion, T, fig. 3, on a shaft, t', held in bearings, t, as shown. At the end of the shaft t' is the roller h, which, in connection with a similar one immediately below it, draws the wire from the spool and pushes it on through the hollow shaft p and the grooves, in the clamps, as

before described. A small pinion, t'' , engages with a similar one attached to the lower roller h , and gives the latter motion. A quarter-wheel, $H'' H''$, shown tinted in fig. 1, is keyed on the shaft F' , and its teeth engage, in revolving, with those of a pinion, U , on a shaft, w , having bearings, $W' W'$, fig. 3. On the end of this shaft is a bevel-pinion, W , which gears into the bevel-pinion X , on the aforesaid hollow shaft p . This pinion has a hole to correspond with the bore of the said shaft, or is set on the end of the shaft, as shown in fig. 1. At the opposite end of this shaft p is another bevel-pinion, O , engaging with a similar one, O' , (see fig. 1,) to which latter is attached the vertical twisting spindle m , before described; and when U is revolved, the spindle m is simultaneously turned by the revolution of the intervening bevel-gears.

The half-wheel S and the quarter-wheel H'' , when set on the shaft in the position shown in fig. 1, and in this correlation with the other parts, will engage with their respective pinions T and U , and cause the timely revolution of the latter to draw and push the wire, and lock the same when cut off, in the manner before described. The cutter f is pivoted to a lever, f' , at f'' , the said lever being pivoted to the frame at f'' . An arm, Q , the dotted outline of which is shown in fig. 1, is keyed on the shaft F , and when in the position shown, will, in revolving, strike against the oblique edge of the lever f' , and cause the latter to thrust the cutting-point of the cutter f against the wire n and the notched plate l , thereby securing the former. On each side of the clamps are plates, i and i'' , fig. 2, the distance of which plates apart corresponds to the length of the fagots, and are for holding them properly in the clamps, so that their ends shall be even when clamped and bound. The plate i'' is provided with a circular door, i''' , hinged to the plate at v . The plate i has a circular disk, i' , not hinged, but supported centrally by an arm, V''' , bolted to an upright, V' , forming part of a horizontal bar, V , supporting the whole. This bar has a longitudinal motion in guides $B' B'$, forming part of the plate B'' , by which the guides are secured to the frame C . The disk i' is thus provided with a horizontal motion, and by this motion the bundles of fagots are thrust out of the clamps, when the wire is locked, and the clamps relaxed, as before mentioned. The door i''' is provided with a spring at its hinge, v , exerting its tension to keep the door vertical, but sufficiently yielding to permit the bundle of fagots to be thrust out by the disk i' . The door is borne down to the position shown by the red lines in fig. 2, whereby it forms a slide connecting with the apron Z , which latter delivers the wood out of the machine. This plunger or disk i' is operated by means of an arm, R , on the shaft F , which arm, in revolving, strikes against a lever, V' , which is pivoted at m''' to an upright, m'''' , standing on and forming part of a projection, m'''' , figs. 1 and 3, from the said plate B'' . A vertical spring, q , returns the lever V' , and consequently the disk i' , to their usual positions after the arm R has passed. The plates i and i'' are bolted to the frame-bottom C' by bolts v' , as shown at fig. 2.

The drawings exhibit the relative positions of all the movable parts of the machine, and when so arranged the cams, wheels, boxes, cutter, plunging-disk, and other devices will perform their different functions at the proper time, and without interference with the other parts or with each other.

When the boxes pass from over the clamps, after having discharged the fagots therein, the bottoms, d' , are thrown up and spring into the catch a'' , before described, as each one passes over the roller A'' . If, as is sometimes the case, they do not catch then, a broad spring, M''' , consisting of a bent metallic sheet, having the vertical part, M'''' , bolted to the frame C , as shown in fig. 1, presenting a surface immediately underneath the chute, and between the belts B , comes in contact with the box-bottom d' and closes it. The end which thus comes in contact with the bottom, d , is over the roller, as shown in the drawing, and closes the bottom before the box comes in position under the chute. The boxes are attached to the belt by clasps at middle points between the ends of the boxes, so that they can pass over the rollers without straining the belt, as shown at D' , fig. 1.

The working size of this machine is about five or six feet long, and the other dimensions in proportion, the frame, rollers, and chute being built of wood, and the other parts of steel and iron.

The advantages of this machine consist in the rapidity with which it performs the work, thus dispensing with the great number of persons required heretofore for bundling and tying fagots of kindling-wood for market. The cost of the wire is estimated to be less than the hemp-strings now used.

I am aware that a machine for tying kindling-wood has been invented, but its construction and mode of operation are totally dissimilar from mine. The machine spoken of has removable boxes, requiring a number of attendants to keep them filled by hand. They are then carried and placed in the machine, which passes the wire around the bundle. This machine has no resemblance to mine in any feature, and has been found impracticable and worthless.

I am aware that the bottoms of coal-cars have been so arranged as to trip and discharge their contents, but this I do not claim.

I claim as new, and desire to secure by Letters Patent—

1. The grooved semicircular clamps $G G'$, constructed as described, pivoted together and to the standards g'' at u , and provided with projections g , pivoted lifter n' , spring e , and points b'' , all operating as described, for the purpose specified.

2. The grooved semicircular clamps $G G'$ in combination with the spring-cams $E E'$, substantially as described, for the purpose specified.

3. The boxes D , upon the endless belts B , constructed as described, having the hinged bottoms d' , operated by the catch a'' and arm b to permit the fagots to fall between the jaws $G G'$, constructed and operating, substantially as described, for the purpose specified.

4. The guide e , having the angular slot e' , in combination with the chute E''' , sliding bottoms $e'' e'''$, angular slotted plate j , and spring o , substantially as described, for the purpose specified.

5. The combination of the rollers h , hollow shaft p , bevelled gears $O X$, bevel-gears $O' W$, the latter upon shaft w , slotted spindle m , shaft t , segmental gear-wheel S , and the wire-cutter f , substantially as described, for the purpose specified.

6. The plunging-disk i' , supported centrally upon the arm V''' by means of the right-angular arm V'' V , and operated through the plate i by means of the pivoted spring-lever V' and arm R upon shaft F , constructed to operate as herein described, for the purpose specified.

7. The spring-door i'' , hinged to the vertical plate i'' , and operated by means of the rags passing between the clamps G G' , under the impulse of the plunger i' , substantially as herein shown and described.

8. The lifting-lever n' , for lifting the severed end of the fagot-wire n , substantially as shown and described.

9. The spring M'''' , for closing the bottom, d' , of the fagot-boxes, substantially as shown and described.
